UNITED STATES PATENT OFFICE.

JAMES E. FROMAN, OF EVANSVILLE, INDIANA.

BABY CARRIAGE.

Application filed January 5, 1922. Serial No. 527,082.

To all whom it may concern:

Be it known that I, JAMES E. FROMAN, a citizen of the United States, residing at Evansville, in the county of Vanderburgh 5 and State of Indiana, have invented certain new and useful Improvements in Baby Carriages, of which the following is a specification.

This invention which relates to baby carriages, has for its objects the provision of, first, an improved mounting for the body of the carriage whereby the latter is freely suspended from a spring frame, thus absorbing the major portion of the shocks and jars to which the carriage is subject, making easy riding for the child; second, a novel detachable suspending connection between the frame and the body of a baby carriage whereby the connection is automatically 10 maintained in securely fastened condition by the weight of the body of the carriage and of the child if the body is occupied; third, an improved suspension for the body of a baby carriage embodying hinged bails and 15 connections for their attachment to the frame of the carriage, whereby the body may be suspended from the frame, or, if detached therefrom may be conveniently carried about or suspended in other places.

30 My improvements are not necessarily limited to use in connection with baby carriages as the essential features of the invention may be embodied in porch beds, invalid beds, porch swings, hammocks, toys and 35 analogous devices.

The particular improvements represented by the various features and combinations of my invention are set forth fully herein-after and recited in the appended claims.

40 The showing of the invention is to be considered as illustrative, instead of restrictive, of the scope thereof as modifications may be resorted to.

In the accompanying drawings:

45 Figure 1 is a perspective view of the baby carriage; and

Figs. 2, 3, and 4, detail views of the suspending connector.

The body is shown at 1 and it is preferably provided with a hood 2 although hood forms no part of the present invention nor does the connection 3 between the hood and body, said connection being set forth and claimed in another application executed of 50 even date herewith.

The running gear and handle may be of any desired form or construction.

The body 1 is supported by a frame 4 which, in the form shown, lies substantially in a single plane and is suitably connected 60 to the running gear.

I wish it to be understood, however, that I do not limit myself to the particular frame shown but whatever frame 4 is used, it is provided with springy or resilient extensions 5 which support the body 1 and absorb to a considerable degree the shocks so that the child rides comfortably. The extensions 5 are provided with hollow sockets 6 in their ends. Detachably received in said 70 sockets 6 are V-shaped expanding coupling 7 formed of springy metal having arc-shaped upper parts 8.

Handles or bails 9 which are pivoted or jointed at 10 to pieces 11 on the body 1 are 75 provided with tubular or cylindrical parts 12 which are inserted in the parts 8 of coupling 7 before said couplings 7 are forced downwardly into sockets 6, whereby the bails 80 swingly suspend the body 1 from the extensions 5 and yet permit bodily detachment of the body by simply drawing the couplings 7 out of the sockets 6.

The spring supports or extensions 5 and the joints 10 and rockable parts 12, afford 85 a means for absorbing shocks and allow movement up and down and lengthwise.

By detaching the body from the extensions 5, the handles 9 may be used to carry the body from place to place or to suspend it 90 in a train, car, automobile, or other location, thus converting the body into a baby basket.

By lengthening and strengthening the frame 4 and the extensions 5, the principle of the invention may be carried out in a 95 porch bed, invalid bed, porch swing, etc. In lieu of the body 1, a hammock or cot shaped frame may be used.

What I claim is:

1. In a baby carriage, the combination 100 with a supporting frame having springy extensions, of a body provided with pivoted handles or bails adapted to be suspended from said springy extensions.

2. In a baby carriage, the combination 105 with a supporting frame, of a body and bails or handles pivoted to the body, and means rockably or rotatably connecting the bails to the frame for forward and rearward swinging.

3. In a baby carriage, the combination with a supporting frame having sockets, of expandible couplings detachably received therein, and a body provided with bails or handles adapted for attachment to, or detachment from said couplings, and rockably or rotatably mounted therein.
4. In a baby carriage, the combination with a supporting frame having sockets, of 10 expandible V-shaped couplings having arc-

shaped parts and composed of springy material, said couplings having their converging parts detachably received in the sockets, and a body provided with bails or handles adapted to attachment to, or detachment from, said arc-shaped parts of the couplings and rotatably or rockably mounted therein.

In testimony whereof I affix my signature.

JAMES E. FROMAN.
